DIAPER

Dorothy L. Miller, Casper, Wyo., assignor of one-fourth to Stanton A. Miller, one-fourth to Sally Jourgensen, and one-fourth to John L. Jourgensen, all of Casper, Wyo.

Application October 3, 1949, Serial No. 119,237

2 Claims. (Cl. 128—287)

1

This invention relates to diapers and more particularly to diapers for association with diaper covers to thereby produce an improved diaper and diaper cover combination for infants.

One of the objects of the invention is to produce an improved diaper for so associating with a diaper cover that an efficient combination garment will result.

Another object is to produce a diaper for use with a non-absorbent diaper cover of the type having holding straps at the front and back thereof, and when associated with the diaper cover and both worn by an infant the area of the cover which will be in contact with the infant's skin to cause any discomfort will be a minimum.

Another object is to so construct a diaper for use with a non-absorbent diaper cover having front and back diaper holding straps that it will present a non-wrinkled surface for contact with the skin of the infant during the entire period of wearing.

Another object is to so construct a diaper for association with a diaper cover that the diaper can be quickly and easily attached to the cover in a non-slipping condition and when associated with the cover and being worn by an infant it will be fully covered and free of any bulges and wrinkles causing discomfornture, besides being unsightly.

A more specific object is to produce a diaper which will have such a shape that it can be fully covered by a diaper cover constructed from plane figure material, the ends of which are of different width and are to extend around the girth of the wearer, and further are of such shape that they can be connected to straps at such ends by being folded around said straps.

Yet another object is to produce an improved diaper which can be attached to a diaper cover by having its ends folded around straps of the diaper cover, which straps will be at the front and back of the wearer when the cover is being worn.

Other objects of the invention will become apparent from the following description taken in connection with the accompanying drawings in which:

Figure 1 is a perspective view of a diaper and diaper cover combination having an improved diaper embodying my invention, said view showing the manner in which it is to be fastened on the wearer;

Figure 2 is a view of the assembled diaper and diaper cover in a laid out condition before being put on the wearer;

Figure 3 is a view of a corner of the diaper

2 showing its construction for attaching to a holding strap on the diaper cover;

Figure 4 is a plan view of another form of diaper;

Figure 5 is a view showing the diaper of Figure 4 assembled with a diaper cover constructed in the same manner as the one shown in Figures 1 and 2;

Figure 6 is a sectional view taken on the line 10 6—6 of Figure 5; and

Figures 7, 8 and 9 are views showing yet another diaper so constructed as to embody the invention, said diaper being made from a rectangular sheet of absorbent material which is folded in a particular manner to obtain the proper shape for association with the diaper cover and to be held therein.

Referring to the drawings in detail, there is disclosed in Figures 1 to 3, inclusive, a diaper cover C and a diaper D embodying my invention. The diaper cover C is of special construction being disclosed and claimed in the copending joint application of myself and Stanton A. Miller, Ser. No. 77,944, filed February 23, 1949, now Patent Number 2,591,182 for "Pants." The improved diaper D embodying my invention is constructed to be used with this particular type of diaper cover, or one of similar construction, and the two together produce a novel diaper and diaper cover combination.

The diaper cover comprises a sheet 10 of a shape similar to an isosceles trapezoid, as is apparent from Figure 2. The diaper cover is preferably made from material which is water proof, or some other type of material which is relatively non-absorbent. Such material can be plastic sheeting or a synthetic fabric such as nylon. The isosceles trapezoid sheet has its edges folded over and sewed in such condition in order to form a smooth edge. The widest end of the diaper cover is arranged to extend across the back of the wearer when the diaper cover is being worn, and the narrowest end is arranged to extend across the front of the wearer. These ends are provided with any suitable securing means such as snaps 11 shown. Each end has two snaps on each side and the snaps so arranged that when the diaper cover is placed upon an infant and the snaps closed to secure the ends together, a pair of pants will be provided, as is readily seen from Figure 1 wherein the snaps at one side of the cooperating ends are snapped together and the other snaps are illustrated as being in a condition just prior to being snapped together. The diaper cover, at its ends,

carries cross holding straps. The holding strap at the wide end of the isosceles trapezoid sheet is indicated at 12 and the holding strap at the narrow end is indicated at 13.

My improved diaper is made of a suitable absorbent material and can be either of a type material which is disposable or a type of material which can be washed for reuse. The diaper is in the form of a sheet 14 having the shape of an isosceles trapezoid, the length of which is substantially the same as the length of the diaper cover. The width at its widest and narrowest ends will be slightly less than the corresponding widths of the diaper cover. At each corner of the sheet 14 of the diaper there is provided a cut 15 as best illustrated in Figure 3. This cut is in the form of a T with the leg 16 extending inwardly from the side edge of the sheet to the cross cut 17 which is inwardly of the said side edge and approximately parallel to the side edge. The T cuts at the wider end of the diaper have leg cuts approximately 2 inches long and the arm cuts are approximately $\frac{3}{4}$ inch long, which will be approximately the same width as the holding straps. Of course, if the holding straps should be wider or narrower, the cross cuts 17 can be varied accordingly. The leg cuts at the narrower end of the diaper are approximately $1\frac{1}{4}$ inches long and the cross cuts will be of a proper length to receive the holding strap.

Figure 2 discloses the manner in which the diaper is assembled with the diaper cover so that the diaper will be held in the proper relation with the diaper cover by the holding straps and thus will always remain in proper position in the diaper cover and not shift relative to said diaper cover during wearing. In assembling the diaper to the diaper cover, the diaper will be laid on the inside surface of the diaper cover with the ends of the diaper superimposed on the holding straps. The leg cuts 16 will then be spread apart and the diaper material on each side of the leg cuts positioned beneath a holding strap. The holding straps will then overlie the diaper which is cut by the leg cuts 16 and will pass through the cross cuts 17 and to remain beneath the diaper. With this assembling of the diaper to the diaper cover, substantially the major portion of the holding straps will be covered by the diaper. Thus, the diaper material will be next to the skin of the infant and will protect the infant's skin from any chafing by a rubbing action of the material of the straps. The wider end of the diaper will extend beyond the strap 12 of the diaper cover a sufficient extent to be superimposed over the diaper cover end, and particularly that portion outwardly of the holding straps. The narrower end of the diaper will be slightly short of the corresponding end of the diaper cover in order to not cover the snaps.

In Figures 4, 5 and 6 another diaper structure is disclosed, said diaper being indicated by the numeral D¹. As shown in these figures, the diaper has a body portion 18 which is of isosceles trapezoidal shape to fit the diaper cover C and have its edges lying within the edges of the said diaper cover. The ends of the body portion of the diaper have integral extensions 19 and 20 which are arranged to fold over the body portion, the folds being made along the dashed lines as indicated in Figure 4. The extension 19, which is at the widest end of the isosceles trapezoid body portion 18, has its sides arranged in outwardly converging relation and the con-

vergence is folded over the body portion. These sides will coincide with the sides of the body portion. The other extension 20 at the narrower body portion 18 has its sides diverging outwardly and the divergence is such that when the extension is folded over the body portion these sides will coincide with sides of the body portion.

The diaper D¹ is associated with the diaper cover C in a manner well illustrated in Figures 5 and 6. When the diaper cover is laid out flat with its holding straps on the upper side, the diaper D¹ will be laid on the diaper cover and the extensions 19 and 20 pushed underneath the holding straps 12 and 13. After this is done the extensions will be folded back onto the body portion of the diaper and thus over the holding straps. The holding straps will then be substantially covered so they will not contact the skin of the infant and cause irritation. The extensions 19 and 20 are of a length substantially less than half the length of the body portion 18, thus they cannot, when folded over the body portion, present any bulkiness at the center of the diaper which will be that portion which is in the crotch of the infant.

In Figures 7, 8 and 9 there is disclosed still another diaper which is constructed from a rectangular sheet of absorbent material and is so folded that there will be provided a diaper having a body portion of the shape of an isosceles trapezoid and additional integrally united extensions at the ends for folding over the body portion and providing for the attaching of the diaper to the holding straps of the diaper cover. The diaper shown in Figures 7, 8 and 9 is indicated generally by the letter D² and the construction involved is primarily intended for a diaper which can be made from cloth material and thereby permit it to be washed for reuse. As best shown in Figure 7 the diaper D² is made from a single sheet of material 21 of rectangular shape. This rectangular sheet is folded along a central cross-wise line indicated at 22, thus producing a substantially square double thickness sheet. With the sheet in this folded condition, it is then folded along two lines indicated at 23 and 24. These lines extend from one corner of the square double thickness sheet in diverging relation across the sheet to points at the remote sides from the beginning corner and substantially centrally of the said sides. The resulting folded construction will then be as indicated in Figure 8 and there will be provided a body portion indicated at 25 having an isosceles trapezoidal shape. This said body portion has triangular shaped extensions at its ends, said extensions being indicated by numerals 26 and 27. These extensions provide means for folding over the body portion so that the diaper D² can be assembled with the diaper cover C in a manner similar to that in which the diaper D¹ is assembled. When the extensions are in folded over condition and attached to the diaper cover, the diaper will be attached to the holding straps and thus an assembly will be provided in which the diaper cannot shift relative to the diaper cover when the combination is worn by an infant. Since both of the extensions 26 and 27 are of triangular shape with sides converging in a direction away from the body portion, no part of the extensions, when in folded condition, will project over the edge of the isosceles trapezoid body portion and thus the diaper cover will completely cover the diaper and present a neat appearance. When the diaper D²

is made from a single sheet of washable material, the fold lines 22, 23 and 24 can be indicated in the sheet by some contrasting color of thread, or even by printing, and with such a permanent indicia for the fold lines there will be no difficulty for anyone to make the proper folds to produce the diaper D².

It will be seen that in all of my diapers disclosed by the drawings, each has a trapezoidal body shape and means are provided for so assembling the diapers with a trapezoidal shape diaper cover having holding straps at the ends thereof that the diapers can be attached to the holding straps so shifting of the diapers relative to the cover will be prevented. In the diapers shown in Figures 1 to 3, the attaching of the attaching of the diaper to the holding straps is accomplished by T-shaped cuts at the corners of the diaper, whereas in the other two diapers, D¹ and D², the holding is accomplished by extensions which are arranged to be folded over the holding straps with the straps received between the extensions and the body portion when in folded condition. When folded, these extensions will be within the outlines of the diaper cover.

Being aware of the possibilities of modifications in the various diapers disclosed and their association with a diaper cover of the type shown, all without departing from the fundamental principles of my invention, it is to be understood that the invention is not to be limited in any manner except in accordance with the appended claims.

What is claimed is:

1. A diaper of absorbent material having the shape of an isosceles trapezoid and for use with a diaper cover made from a sheet of material hav-

ing the shape of an isosceles trapezoid and being provided with permanently attached cross holding straps at its ends, said diaper at its corners being provided with T-shaped cuts with the leg portion of each cut extending inwardly from the side edge of the diaper so that the diaper can be parted along the leg portion and inserted beneath a strap and thereby cause the strap to extend through the cross portion of the T-shaped cut.

- 5 10 15 20
2. A diaper comprising a single sheet of absorbent material free of folding, said sheet having four corners and being provided with a slit at each corner which extends inwardly from an edge and then laterally so there will be such configuration that a part of the diaper material adjacent an edge can be inserted beneath a holding strap of a diaper cover whereby the diaper will be held from slippage relative to the cover yet substantially all the length of the strap equal to the width of the diaper will be covered by diaper material.
